UNITED STATES PATENT OFFICE

101,178

DESIGN FOR A TEXTILE FABRIC OR SIMILAR ARTICLE

Albert Roth, New York, N. Y.

Application June 10, 1936, Serial No. 63,206

Term of patent 3½ years

To all whom it may concern:

Be it known that I, Albert Roth, a citizen of the United States of America, residing in the Borough of Manhattan, in the city, county, and State of New York, have invented a new, original, and ornamental Design for a Textile Fabric or Similar Article, of which the following is a specification, reference being had to the accompanying drawing forming part thereof.

The figure of the drawing is a plan view of a piece of textile fabric embodying my design.

The design unit is indicated on the drawing by dot and dash lines, which unit is repeated in regular succession, as indicated by the extensions beyond the unit boundaries.

I claim:

The ornamental design for a textile fabric or similar article substantially as shown and described.

In witness whereof, I have hereunto signed my name.

ALBERT ROTH.
